CRACKING PROCESS

William C. Offutt and Merald Clark Fogle, Oakmont, Pa., assignors to Gulf Research & Development Company, Pittsburgh, Pa., a corporation of Delaware

Application April 15, 1946, Serial No. 662,213

10 Claims. (Cl. 196—66)

1

This invention relates to a cracking process, and more particularly to a process of cracking petroleum hydrocarbons to produce gasoline.

It is ordinary practice in the petroleum refinery art to crack petroleum hydrocarbons such as heavy residual oils by the use of heat with or without a catalyst, to obtain gasoline. All of these processes, however, yield in addition to gasoline substantial proportions of other products such as, for example, gases, gas oil, tar and coke. It is desirable to obtain the largest possible amount of good quality gasoline while at the same time producing the smallest possible amount of other products and particularly fuel oil.

One of the methods which has been applied to increase gasoline yield has been the recycling of the gaseous products to the reaction zone and the present invention is directed to an improved process which may include this use of gaseous products. Some of these processes have utilized relatively light stock which was obtained by first separating the heavy stock before sending it to the reaction zone.

It is an object of this invention to crack heavier petroleum hydrocarbons to obtain a high yield of gasoline by the use of gaseous hydrocarbons.

It is a further object of this invention to crack a heavy residual oil to obtain a high yield of gasoline while producing only a small amount of by-products such as fuel oil, by utilizing gaseous hydrocarbons.

These and other objects of this invention are achieved by the present process wherein a heavy petroleum hydrocarbon fraction is partially vaporized in a coil and then mixed in a reaction zone or chamber with a hot gas, preferably gaseous hydrocarbons. The gases are preheated in a coil separate from the heavy petroleum hydrocarbons before being passed into the reaction chamber at a temperature sufficiently high to add substantial heat energy to the already heated heavy petroleum hydrocarbons. The temperature and time of residence of the heavy petroleum hydrocarbons in the preheating coil should be sufficient to effect substantial vaporization and to crack some of the constituents but not sufficient to cause substantial coke deposition in the preheating coil. This temperature should be in the range 850° F. to 950° F. (at the coil outlet) and preferably about 900° F. depending on the stock treated. When the hot gases contact this material, preferably when both enter the top of the vertical reaction chamber, further vaporization occurs, the vapors are subjected to fur-

2

ther cracking and the unvaporized residual constituents pass quickly to the bottom of the reaction vessel without much opportunity to coke.

The temperature of the hydrocarbon gases should be substantially higher than that of the residual oil charged but not so high as to cause substantially instantaneous coking upon contact with a heavy oil. For this purpose the gases should be heated to a temperature in the range 10 1000° F. to 1200° F. and preferably 1100° F. It will be understood that the temperature of the gas may be varied depending upon the amount of the gas compared to the amount of charge stock, residence time in the reactor, temperature of the charge, and other factors, but these should be adjusted to allow for the above preferred gas temperatures. Coking will not take place to any substantial extent at the reaction temperatures if the time of reaction is so controlled to prevent 15 such coking. The invention contemplates a temperature high enough to cause coking if a soaking period were allowed, but this period of time should be shortened to avoid the coking. The temperature of the heated oil is not necessarily 20 raised above that of the coil outlet temperature, the hot gases rather serving to cancel out some of the cooling effects which come into action when the material is discharged into the reaction 25 chamber. The action of the added gases contributes a vaporizing effect.

The charge is a heavy petroleum oil containing residual constituents such as reduced crude and it is a feature of the invention that this can be handled directly without preliminary separation 30 of residual constituents.

The gases used may be obtained from an outside source such as a hydrocarbon gas from a cracking unit, steam, or other inert gas. Preferably however, the gases used are a part of the 40 entire gaseous product, having a boiling point below the gasoline fraction, recycled from the same cracking system in which they are used. Use of a part of such entire gaseous products avoids any necessity for fractionating the gases. Pressure 45 conditions may be varied depending upon the degree of cracking desired, type of charge, temperature, etc., but it will usually be in the range of from 100 to 2000 pounds per square inch and preferably 500 to 1000 pounds per square inch.

The amount of added gas may be varied greatly depending upon the amount available, the various temperatures and pressures of operation, the capacity of the apparatus, the olefinic content of the gas and other factors. The preferable quantity of gas, however, should be in the

range 50 to 300 liquid volume per cent of the oil charge and preferably about 75 liquid volume per cent to about 100 liquid volume per cent of the oil charge.

The apparatus used for the process may be any of the conventional types and the reaction chamber is preferably an elongated vertical vessel.

Cracking processes in which only one coil is used to heat the charge are known as "single coil" systems. The invention is applicable to such systems and also to systems of the "two coil" type wherein heavy oil is heated in one coil and light oil, which may be recycled from within the process, is heated in a second coil at a higher temperature and the two discharged into a reaction chamber. In using a "two coil" system the light recycle oil may be heated to a temperature in the range 950° F. to 1050° F. prior to entering the reaction chamber. In a preferred embodiment of the invention it is also desirable to so control the operations of cracking and tar separation so as to produce and separate out a heavy tar of, for example, 4° API gravity or heavier, in other words to a material not directly saleable as fuel oil. This tar may then be blended back with a portion of the light recycle oil of the process to form a saleable fuel oil. Operating under these conditions, a greater gasoline yield is obtained.

Specific embodiments of the present invention are illustrated in the drawings wherein:

Figure 1 is a flow sheet of the process of the present invention as applied to a so-called "single coil" system;

Figure 2 is a flow sheet of the process of the present invention as applied to a so-called "two coil" system, and

Figure 3 is a flow diagram of a reactor alternative to the one shown in Figures 1 and 2.

Heretofore, in the operation of so-called "single coil" cracking units on oils containing residual constituents, it has been necessary to employ relatively mild temperatures and relatively low conversions per pass, in order to avoid excessive coke formation. As a result, such operations have tended to result in relatively poor yields of gasoline. However, our invention makes it possible to carry out the cracking of a wide variety of residual oils in apparatus of the "single coil" type under such conditions that higher yields of gasoline are obtained, but without causing excessive deposition of carbon or coke, especially in the cracking coil. By maintaining proper conditions in the coil, deposition of coke at that point in the system is prevented. Higher temperatures may be maintained in the reaction chamber by the addition of heat energy from added gases, but on account of the relatively short time of contact of the heavy oil in the reaction chamber, coking is reduced to a minimum and any coking as may occur is obviously of less consequence than would be the case if the same amount of coking were to take place in a pipe coil of restricted cross-sectional area. On the other hand, the high temperature and relatively long time of contact of the lighter oil vapors in the reaction chamber makes it possible to obtain a substantially higher degree of cracking, and higher degree of conversion per pass, than could otherwise be secured. As a result, higher overall degree of cracking is obtained, and the yield and quality of the gasoline product are enhanced.

With reference to Figure 1 it will be seen that the charge, which is reduced crude in this instance, is pumped by means of pump 10 through

conduits 11 to heating coil 12 where it is brought up to a temperature in the range 850° F. to 950° F. Gas recycled from the process is sent to heater 14 where it is brought up to a temperature in the range of 1000° F. to 1200° F. and passed to a reaction chamber 15 at a point or near the top thereof and adjacent the point at which the hot oil is introduced. The cracking products are taken from the reaction chamber 15 by conduit 16 to a separator 18 wherein the products are separated into two fractions, one relatively heavy and the other relatively light. The heavy fraction or bottoms is sent by conduit 19 and preheater 20 to tar stripper 21. The tar stripper may operate in any known manner with or without the use of steam or an extracting material such as naphtha. This heavy residuum from the separator is thus separated into the three portions; reduced tar, heavy recycle stock, and an overhead which, together with the overhead from separator 18, is passed to the fractionator 23 from which light oil is removed as bottoms and returned to the oil heater, or mixed with reduced tar to produce fuel oil as will be hereinafter explained. The overhead from the fractionator 23 is passed by conduit 24 to a stabilizer 26 wherein the gaseous products are separated from the gasoline. The overhead from the stabilizer is sent to a gas condenser 27 where in the difficultly condensable gases may be removed and the condensed gas ordinarily rich in C₃ and C₄ hydrocarbons is returned to the gas heater 14.

Light recycle oil from fractionator 23 may be returned by conduit 29 to oil heater 12, or a portion of it may be used to blend with heavy tar to make a saleable fuel oil. The cracking by the present process produces a large amount of gasoline and this is increased by so controlling distillation to produce a quantity of heavy tar (4° API gravity or heavier) rather than a heavy oil which might be used directly as a fuel oil. The tar produced is utilized by mixing therewith a small proportion of the light recycle oil to obtain a fuel oil. This is accomplished by tapping conduit 29 by means of a conduit 30 and removing a portion of the light oil to admixture with the reduced tar coming from the tar stripper by conduit 31. Conduit 32 provides a means for returning light recycle oil to the reactor as a quench. Most of the light recycle however is subsequently passed to the reactor and the ultimate yield of gasoline is higher than if a saleable fuel oil were separated out instead of a low gravity tar.

Alternatively, but not shown herein, it may be desirable to use a gas absorber in the place of the gas condenser. In that instance, an absorbing material, such as naphtha or gas oil, may be used to absorb the gases and the absorbed material may be passed to another vessel in which the absorbed gases are then stripped from the naphtha and sent to the gas heater. The naphtha or gas oil may be recycled continually between the gas absorber and the gas stripper.

With reference to Figure 2 there is shown a flow sheet of the process of the present invention as applied to a so-called "two coil" system. A charge of reduced crude or other heavy oil is sent to heater 40 where it is heated up to a temperature in the range 850° to 950° F., then passed to reaction chamber 41. A light recycle oil which is recycled from the process is heated in heating coil 43 and subsequently charged to the reaction chamber together with the heavy oil. There is

further provided a gas heater 44 for heating the gas recycled in the system and this gas is heated to a temperature in the range 1000° F. to 1200° F., and is also introduced into the reaction chamber at a point adjacent the introduction of the light and heavy oil. The reaction products from reaction chamber 41 are passed into separator 46 by means of conduit 47 wherein they are separated into light and heavy ends. The heavy material passes by conduit 48 through a tar pre-heater 49 to a tar stripper 50. This tar stripper may operate in any of the conventional manners with or without the use of steam, but essentially the heavy ends from separator 46 are divided into three portions, one a reduced tar product, another a heavy recycle oil, which is passed by conduit 52 to the heavy oil heater, and an overhead fraction. The lighter overhead material from the tar stripper is passed to a fractionator 55 as is also the overhead from separator 46, which passes to the fractionator 55 by conduit 56. The fractionator separates the materials into a light and a heavy product, the light product passing by conduit 58 to a stabilizer 59 and the heavy product, which is a light recycle oil, is passed by conduits 60 and 61 to the light oil heater 43. A portion of the light oil, however, may be bled off by conduit 62 for admixture with the reduced tar from conduit 63 to form fuel oil when operating under conditions such that reduced tar is formed instead of a heavy oil which would be saleable as fuel oil, as explained in Figure 1 above. Conduit 64 provides a means for returning light recycle oil to the reactor to act as a quench. In the stabilizer 59 the gasoline product is taken off as bottoms and the overhead gases passed to a gas condenser 65 by means of conduit 66 wherein the condensable gases are condensed and returned by conduit 67 to the gas heater 44 and the non-condensable gases are passed off by conduit 68.

While the two-coil cracking system may not be as flexible as the single-coil system, it does have the advantage that the light oil may be heated to a higher temperature than the heavy oil without coking and thus more gasoline is obtained.

Figure 3 shows an alternative method of operating the reaction chamber from that shown in Figures 1 or 2. In this case the preheated oil and gas inlets are at a point in the chamber substantially below the top thereof and means are provided for venting the vapors at the top of the reaction chamber. Some of the vapors may pass out with the liquid at the bottom of the chamber as shown in Figures 1 and 2.

In the practice of the present invention the unvaporized oil in the coil, as well as in the reactor, is subjected to vis-breaking, and the coking of this reduced amount of residuum is avoided by removing it rapidly from the bottom of the reactor. Thus, no accumulation of liquid should be permitted in the bottom of the reactor. The charge emerges from the coil to the reactor as a mixture of vapors with more or less subdivided drops or very small slugs of unvaporized liquid. This liquid because of its density will drop or be projected quite rapidly to the bottom of the reactor where it will pass out at once. The vapor on the other hand will not pass through the reactor as rapidly and will mix with the hot gas injected from the gas heating coil. Thus the time of residence of vapors is greater than it would be in a coil since normal vapors in a coil travel more rapidly than unvaporized liquid. Thus in the present process the vapor is subjected to a

longer time of treatment than it would be in a coil.

The present process effects a vis-breaking of the residuum in order to reduce its amount as far as possible. The intention in the process is to make as little and as heavy a tar as possible, since it may subsequently be converted to marketable fuel oil by blending with some of the light recycle oil. In this manner the largest possible amount of gasoline is produced. The process thus is adequately adapted to deal directly with heavy petroleum distillates to obtain the maximum amount of gasoline with the minimum amount of fuel oil.

15 Thus we have described a new and useful process for cracking heavy petroleum hydrocarbons to obtain a high yield of gasoline.

What we claim is:

1. A process for cracking a heavy petroleum hydrocarbon fraction containing residual constituents to obtain gasoline without preliminary separation of such residual constituents which comprises heating said heavy fraction at a temperature and for a time sufficient to cause partial vaporization but insufficient to cause coking, heating a gas to a temperature substantially higher than the temperature of heating of said heavy fraction but not so high as to cause substantially instantaneous coking upon contact with said heated heavy fraction, charging both vaporized and unvaporized portions of said heavy fraction together with said heated gas to a reaction zone containing no catalyst and further vaporizing said unvaporized portion and subjecting it to vis-breaking, thereby producing minimal amounts of unvaporized residuum, passing the unvaporized portions of said heavy fraction rapidly through said reaction zone without substantial coking, and maintaining the vaporized portions of said heavy fraction in said reaction zone for a time sufficient to cause substantial cracking of said vaporized portions.

2. A process for cracking a heavy petroleum hydrocarbon fraction containing residual constituents to obtain gasoline without preliminary separation of such residual constituents which comprises heating said heavy fraction at a temperature in the range 850° to 950° F. and for a time sufficient to cause partial vaporization but insufficient to cause coking, heating a normally gaseous hydrocarbon mixture to a temperature substantially higher than the temperature of heating of said heavy fraction but not so high as to cause substantially instantaneous coking upon contact with said heated heavy fraction, charging both vaporized and unvaporized portions of said heavy fraction together with said heated gas to a reaction zone containing no catalyst and further vaporizing said unvaporized portion and subjecting it to vis-breaking, thereby producing minimal amounts of unvaporized residuum, passing the unvaporized portions of said heavy fraction rapidly through said reaction zone without substantial coking, and maintaining the vaporized portions of said heavy fraction in said reaction zone for a time sufficient to cause substantial cracking of said vaporized portions.

3. The process of claim 2, wherein the temperature of heating of the normally gaseous hydrocarbon mixture is in the range 1000° to 1200° F.

4. A process for cracking a heavy petroleum hydrocarbon fraction containing residual constituents to obtain gasoline without preliminary separation of such residual constituents which

comprises heating said heavy fraction at a temperature in the range 850° to 950° F. and for a time sufficient to cause partial vaporization but insufficient to cause coking, heating a normally gaseous hydrocarbon mixture in an amount between fifty per cent and three hundred per cent by liquid volume of said petroleum hydrocarbon to a temperature in the range 1000° to 1200° F., charging both vaporized and unvaporized portions of said heavy fraction together with said heated gas to a reaction zone containing no catalyst and further vaporizing said unvaporized portion and subjecting it to vis-breaking, thereby producing minimal amounts of unvaporized residuum, passing the unvaporized portions of said heavy fraction rapidly through said reaction zone without substantial coking and maintaining the vaporized portions of said heavy fraction in said reaction zone for a time sufficient to cause substantial cracking of said vaporized portions.

5. A process for cracking a heavy petroleum hydrocarbon fraction containing residual constituents to obtain gasoline without preliminary separation of such residual constituents which comprises heating said heavy fraction at a temperature of about 900° F. and for a time sufficient to cause partial vaporization but insufficient to cause coking, heating a gas at a temperature of about 1100° F. in an amount between seventy-five per cent and one hundred per cent by liquid volume of said heavy petroleum hydrocarbon fraction, charging both vaporized and unvaporized portions of said heavy fraction together with said heated gas to a reaction zone containing no catalyst and further vaporizing said unvaporized portion and subjecting it to vis-breaking, thereby producing minimal amounts of unvaporized residuum, passing the unvaporized portions of said heavy fraction rapidly through said reaction zone without substantial coking and maintaining the vaporized portions of said heavy fraction in said reaction zone for a time sufficient to cause substantial cracking of said vaporized portions and under a pressure in the range of from 100 to 2000 pounds per square inch.

6. The process of claim 5, wherein the pressure is in the range 500 to 1000 pounds per square inch.

7. A process for cracking a heavy petroleum hydrocarbon fraction containing residual constituents to obtain gasoline without preliminary separation of such residual constituents which comprises heating said heavy fraction at a temperature and for a time sufficient to cause partial vaporization but insufficient to cause coking, heating a gas theretofore obtained in the process to a temperature substantially higher than the temperature of heating of said heavy fraction but not so high as to cause substantially instantaneous coking upon contact with said heated heavy fraction, charging both vaporized and unvaporized portions of said heavy fraction together with said heated gas to a reaction zone containing no catalyst and further vaporizing said unvaporized portion and subjecting it to vis-breaking, thereby producing minimal amounts of unvaporized residuum, passing the unvaporized portions of said heavy fraction rapidly through said reaction zone without substantial coking and maintaining the vaporized portions of said heavy fraction in said reaction zone for a time sufficient to cause a substantial cracking of said vaporized portions, separating the reaction products to obtain tar, light and heavy recycle oils, gasoline and gaseous hydrocarbons, recycling said

recycle oils for heating with said heavy petroleum hydrocarbons, and recycling a portion of said gaseous hydrocarbons.

8. A process for cracking a heavy petroleum hydrocarbon fraction containing residual constituents to obtain gasoline without preliminary separation of such residual constituents which comprises: heating said heavy fraction at a temperature in the range 850° to 950° F. and for a time sufficient to cause partial vaporization but insufficient to cause coking; heating a light recycle oil theretofore obtained in the process to a temperature in the range 950° to 1050° F.; heating a normally gaseous hydrocarbon mixture theretofore obtained in the process to a temperature in the range 1000° to 1200° F.; charging both vaporized and unvaporized portions of said heavy fraction together with said heated gas and light recycle oil to a reaction zone containing no catalyst and further vaporizing said unvaporized portion and subjecting it to vis-breaking, thereby producing minimal amounts of unvaporized residuum; passing the unvaporized portions of the charge rapidly through said reaction zone without substantial coking; maintaining the vaporized portions of the charge in said reaction zone for a time sufficient to cause substantial cracking of said vaporized portions; separating the reaction products from said reaction zone into gasoline, light recycle oil, heavy recycle oil, tar and normally gaseous hydrocarbons; recycling the light recycle oil to the light recycle oil heating step; recycling the heavy recycle oil for heating with the heavy petroleum hydrocarbon fraction; and recycling a portion of the normally gaseous hydrocarbons to the gaseous hydrocarbon heating step.

9. A process for cracking a heavy petroleum hydrocarbon fraction containing residual constituents to obtain gasoline without preliminary separation of such residual constituents which comprises heating said heavy fraction at a temperature and for a time sufficient to cause partial vaporization but insufficient to cause coking, heating a gas to a temperature substantially higher than the temperature of heating of said heavy fraction but not so high as to cause substantially instantaneous coking upon contact with said heated heavy fraction, charging both vaporized and unvaporized portions of said heavy fraction together with said heated gas to a reaction zone containing no catalyst and further vaporizing said unvaporized portion and subjecting it to vis-breaking, thereby producing minimal amounts of unvaporized residuum, passing the unvaporized portions of said heavy fraction rapidly through said reaction zone without substantial coking, and maintaining the vaporized portions of said heavy fraction in said reaction zone for a time sufficient to cause substantial cracking of said vaporized portions, the unvaporized portions of said heavy fraction and the products of cracking of the vaporized portions of said heavy fraction being withdrawn through a common conduit at the bottom of said reaction zone.

10. A process for cracking a heavy petroleum hydrocarbon fraction containing residual constituents without preliminary separation of such residual constituents to obtain a relatively high yield of gasoline and a relatively low yield of fuel oil which comprises heating said heavy fraction at a temperature and for a time sufficient to cause partial vaporization but insufficient to cause coking, heating a normally gaseous hydro-

carbon mixture substantially higher than the temperature of heating of said heavy fraction but not so high as to cause substantially instantaneous coking upon contact with said heated heavy fraction, charging both vaporized and unvaporized portions of said heavy fraction together with said heated gas to a reaction zone containing no catalyst and further vaporizing said unvaporized portion and subjecting it to vis-breaking, thereby producing minimal amounts of unvaporized residuum, passing the unvaporized portions of said heavy fraction rapidly through said reaction zone without substantial coking, maintaining the vaporized portions of said heavy fraction in said reaction zone for a time sufficient to cause substantial cracking of said vaporized portions, subjecting the total effluent from said reaction zone to separation to obtain a reduced tar product having an A. P. I. gravity heavier than 4, fractionating the rest of the reaction products to obtain gasoline, gas, heavy recycle oil and a light recycle oil, and combining

a portion of said light recycle oil with said tar to produce fuel oil.
